Primary Examiner — Robert M Spear*Assistant Examiner* — Marissa Cash(74) *Attorney, Agent, or Firm* — Robert Z. Evora, Esq.; Wade C. Yamazaki(57) **CLAIM**

The ornamental design for a drinking cup top, as shown and described.

DESCRIPTION

FIG. 1 is a front view of a drinking cup top showing my new design;

FIG. 2 is rear view thereof;

FIG. 3 is a right side view thereof, with the left side view being a mirror image thereof;

FIG. 4 is a top view thereof;

FIG. 5 is a rear, left side, top perspective view thereof; and, FIG. 6 is a front, right side, top perspective view thereof.

The broken lines indicate elements which do not form part of the claim herein. The shading on the figures indicates transparency.
